Inventor
Alexander J. Watson,
By his Attorney
H. W. Ford Esq.

UNITED STATES PATENT OFFICE.

ALEXANDER J. WATSON, OF PLAINFIELD, NEW JERSEY.

GRIP FOR BOWLING-BALLS AND THE LIKE.

1,139,827.

Specification of Letters Patent. Patented May 18, 1915.

Application filed October 28, 1913. Serial No. 787,705.

To all whom it may concern:

Be it known that I, ALEXANDER J. WATSON, a citizen of the United States, residing at Plainfield, in the county of Union and State of New Jersey, have invented certain new and useful Improvements in Grips for Bowling-Balls and the like, of which the following is a full, clear, and exact description.

0 The present invention relates to improvements in grips or handles for various purposes, and is particularly directed to the provision of a handle or grip to be used in connection with bowling balls and analogous devices.

15 The object of the present invention is to provide a grip or handle which may be readily attached to a bowling ball of the usual type or of a special type, and detached therefrom so that the ball may be thrown or delivered with facility and with a degree of precision that assures practically accurate bowling, by reducing to a minimum the effort and skill which are now necessary to properly deliver a bowling ball and cause it to travel the desired course upon the alley.

20 A further object of my invention is the production of a handle or grip, as above set forth, which may be conveniently held in the hand of the bowler, which will be simple and economical to manufacture, and which will be so constructed that in throwing or making the delivery of the ball it may be released at any part of the swing so that it will leave my device with the facility with which the ordinary bowling ball, at present in use, leaves the hand when released by the fingers of the bowler.

25 My invention is also directed to a grip or handle which by its adaptability may be readily employed as a carrying medium for transporting bowling balls from place to place.

30 Briefly stated, my invention comprises a rigid member or frame and a relatively movable member, the latter of which is arranged to grip a bowling ball and normally retain the same within the rigid member so that as the arm of the bowler is swung or moved in the customary arc preparatory to delivering the ball, the latter will be firmly and securely held against dislodgment, and as the end of the swing is reached the ball may be instantly released by a slight move-

ment of the movable member, as and for 55 the purposes and in the manner which will be hereinafter more specifically described.

50 I shall now proceed to describe my invention with reference to the accompanying drawings, which show its application to a 60 bowling ball, but I would have it understood that my invention is equally applicable to other purposes.

55 In the drawings: Figure 1 is a front elevation partly in section showing my invention applied to a bowling ball. Fig. 2 is a side elevation of the gripping device shown in Fig. 1. Fig. 3 is a front elevation partly in section showing a modified arrangement of my invention, and Fig. 4 is a side elevation of the structure illustrated in Fig. 3.

60 Referring now to the drawings in detail, in which like reference characters are employed to designate similar parts throughout the several views, 7 indicates a bowling ball 75 which is preferably provided, as herein shown, with diametrically opposed sockets or recesses 8. These sockets or recesses may be formed in any suitable manner; in the present instance, being made of metal and 80 countersunk in the surface of the ball, and of a weight and size which will compensate for the quantity of the material removed from the balls in forming the seats therefor so that the equilibrium of the ball will not 85 be affected.

85 The handle or gripping device comprises the frame or fixed member 9, which may be made of any suitable material, and which is preferably of the configuration shown, 90 though it may, of course, be made in any other desired shape, which will suit the purpose. As will be obvious from Figs. 2 and 4 of the drawings, the side arms of this fixed member 9 are formed with the parallel 95 sides 9^a terminating in a preferably rectangular portion to which is suitably secured a boss 10 to provide a housing for the plunger 11, as hereinafter explained.

100 The plungers 11 are normally adapted to engage the sockets 8 as shown in Fig. 1 under the influence of the spiral springs 12, the ends of the springs respectively bearing against the inside of the boss or housing 10 and the shoulder 13 formed on the plungers 105 intermediate of the ends thereof. Each plunger is provided with a slot 14 having a chamfered face which is adapted to be en-

gaged by the projection 15 formed on the ends of the actuating member 16 which is preferably of a resilient or yielding material, such as spring steel or the like, and 5 which is made to conform to the configuration of the frame or fixed member 9, the head or top portion of the actuating member being seated within a slot or cut-out portion 17 formed in the head 18 of the frame 10 9, the under side of the head of the latter being preferably rounded to provide a convenient and positive grip for the hand of the bowler.

Under normal conditions, when the plungers 11 are in engagement with the sockets 8 in the ball, the relative parts will be in the position shown in Fig. 1, the projection 15 on the ends of the actuating member 16 abutting the inside of the boss or housing 10 20 and the plungers being held in engagement with the sockets by the springs 12, the spring 19 mounted on the pin 20 in the head of the yielding member, and seated in the recess 21 formed in the interior of the head of the 25 fixed member or frame 9, serving to maintain the parts in coöperative relation and add security to the grip, so that under the impulse of the centrifugal force developed during the swinging movement of the arm 30 of the bowler the ball cannot pull away or become loosened from the gripping device.

When delivering a ball with my improved device, preferably constructed in the manner described, as the arm of the bowler reaches the completion of the swing and he is positioned to deliver the ball, the actuating member 16 is compressed by the palm of the hand in engagement with the head 22 thereof overcoming the tension of the spring 40 19 and causing the projections 15 on the ends thereof to engage with and travel or move downwardly within the slots 14 in the plungers 11 and force them back against the tension of the spiral springs 12, thereby disengaging them from the sockets 8 and releasing the ball. The position assumed by the parts when the ball is released, is shown in Fig. 3, the outer ends of the plungers protruding through the apertures 23 provided in the respective bosses or housings, the several springs being contracted and the actuating member lying approximately within the plane of the frame or fixed member.

55 In order to secure accuracy of movement of the spring arm with relation to the fixed member or frame 9, I have found it desirable to provide the studs or pins 24 secured to the frame which move in the guide recesses or slots 25 in the head of the fixed member or frame 9.

In the modified form of device shown in Fig. 3, it will be observed, that in lieu of the spiral springs 12 I employ a flat spring 60 65 26 mounted on each side of each plunger,

these springs 26 being suitably fastened to the rigid or frame member and to the plungers as shown.

It will be seen from the foregoing, taken in conjunction with the accompanying drawings, that I have produced a device which provides a positive and powerful grip for the ball and which at the same time is so constructed, that a comparatively slight pressure of the hand will serve to operate 75 the parts and release the ball wherever desired.

While I have described my invention with reference to the specific embodiment shown, it is obvious that my device may be used for 80 other purposes, and that the details of structure may be changed in various ways without departing from the spirit and scope of my invention.

Having thus described my invention what 85 I claim as new herein and desire to secure by Letters Patent is:

1. A gripping device for bowling balls, embodying a rigid yoke adapted to span the ball and provided at its extremities with 90 yieldingly mounted means to engage with the ball and hold it within the yoke, and resiliently mounted means carried by said yoke and adapted to engage with said yieldingly mounted means, whereby a single 95 movement of said resiliently mounted means relative to said yoke will effect the release of the ball.

2. In a device of the character described, the combination with a ball, provided with 100 diametrically opposed sockets, of a gripping device therefor, said gripping device comprising a rigid member and a resilient member mounted thereon and movable relatively thereto, means carried by said rigid 105 member adapted to engage with the sockets in said ball, and means on said movable member whereby the actuation of said movable member will operate to withdraw said engaging means from the sockets in said 110 ball.

3. In a device of the character described, the combination with a ball, of a gripping device therefor having a rigid member and a relatively movable member, means carried 115 by said rigid member having portions normally adapted to engage with said ball at two points thereof and grip the same, and means for operating said movable member to actuate the said gripping means to withdraw them from engagement with the ball and release the same.

4. In a device of the character described, the combination with a ball, provided with 120 diametrically opposed sockets, of a gripping device therefor, having a fixed member and a relatively movable member, means carried 125 by said fixed member and adapted to engage with the sockets in said ball, and means for operating said movable member to actu-

ate said engaging means to withdraw them from engagement with the sockets and release said ball.

5. In a device of the character described, the combination with a bowling ball provided with diametrically opposed sockets, a gripping device therefor embodying a frame, gripping means carried thereby and adapted to engage the sockets in said ball, 10 yielding means for normally maintaining said gripping means in engagement with the sockets in said ball, and a yielding mem-

ber mounted on said frame and operable to engage with said gripping means to move them out of engagement with the sockets 15 in said ball and release the same.

In witness whereof I have set my hand in the presence of two subscribing witnesses this 27th day of October, 1913.

ALEXANDER J. WATSON.
